UNITED STATES PATENT OFFICE.

WILLIAM E. TAYLOR, OF EAST ORANGE, NEW JERSEY, ASSIGNOR TO AMERICAN CAN COMPANY, A CORPORATION OF NEW JERSEY.

HERMETICALLY-SEALED RECEPTACLE.

1,337,491.

Specification of Letters Patent. Patented Apr. 20, 1920.

Application filed January 7, 1916. Serial No. 70,859.

To all whom it may concern:

Be it known that I, WILLIAM E. TAYLOR, a citizen of the United States, residing at East Orange, in the county of Essex and 5 State of New Jersey, have invented certain new and useful Improvements in Hermetically-Sealed Receptacles, of which the following is a specification.

The invention relates to the hermetic sealing of cans and other receptacles made of tin or its equivalent, and particularly to that class of receptacles the body and end or ends of which are provided with outwardly extending flanges united by a separable malleable metal sealing strip which embraces and holds together said flanges with a hermetic closure. Such a receptacle is opened by turning up the end of said strip with the aid of a knife or other suitable instrument, or by the fingers, and then stripping or unwinding the strip from the can flanges, so as to release the end or cover and make the same easily removable.

Many of the cans so closed, especially 25 when they contain certain food products, require to be processed, that is to say, to be subjected to a considerable degree of heat. Such processing usually causes the expansion of the contents to exert a pressure 30 within the can, which is necessary to be resisted by the seal so as to maintain its hermetic character. This pressure is more or less according to the nature of the product which is being packed, varying ordinarily 35 from about six to twenty-seven pounds, more or less.

The invention has several objects in view including the maintaining of the hermetic seal during the sometimes rough handling 40 and transportation of the can, in quantities, during the processing, and thereafter until the can is opened; the keeping of the strip seal securely in its proper place around the flanges of the can; and the easy removal of 45 the strip when the can is intentionally opened.

The conditions to be met in this type of can closure are somewhat difficult, because the strip must be held from accidental displacement by means which will not cause 50 complaint from users that the can is difficult to open; and the holding means which meet both of these conditions must be simple and inexpensive so as not to add materially to 55 the cost of the can or of the sealing opera-

tion. I attain the desired results by utilizing the corner of the can end shoulder as a retaining means against radial displacement of the sealing strip, the latter or a portion thereof being formed to extend slightly over 60 and within said corner.

With such objects in view the invention consists in the parts and combinations thereof hereinafter set forth and claimed, with the understanding that the several 65 necessary elements constituting the seal may be varied in proportions and arrangement without departing from the nature of the invention.

In order to make the invention more 70 clearly understood there is shown in the accompanying drawings means for carrying the same into practical effect, without limiting the improvements in their useful applications, to the particular construction 75 which, for the purpose of explanation, have been made the subject of illustration. In the said drawings—

Figure 1 is a side view of the closed can.

Fig. 2 is a plan view of the same.

Fig. 3 is a partial plan view showing the ends of the sealing strip abutted instead of being lapped.

Fig. 4 is a vertical section of the can end or cover, enlarged.

Fig. 5 is a similar view of the upper end of the can.

Fig. 6 is a similar view of the can with the cover sealed in place thereon.

Fig. 7 is a plan view of the sealing strip, 90 bent or formed into annular shape.

Fig. 8 is a cross section of the same on line VIII—VIII of Fig. 7.

Fig. 9 is a perspective view of a portion of the strip in straight form adapted to be 95 wound onto the can flanges in a known manner.

Referring to the drawings, 1 indicates the body of the can formed at its mouth with an outstanding peripheral flange 2. 3 is the 100 can end or cover formed with a central depression 4 the walls 5 of which are adapted to engage within the walls of the top end of the can, and formed with an outstanding peripheral flange 6 corresponding preferably 105 in position and diameter with the flange 2 so that it may fit therewith in parallel arrangement (Fig. 6). 7 is a packing or ring-liner arranged so that it will be included between the can flanges when the can is sealed. 110

It may be of any suitable material. A composition applied on the interior face of one of said flanges, or an interposed paper ring may be successfully employed. Such a paper 5 or other ring may be fed into place during the closing operation, or it may be preliminarily applied or attached to the can body flange 2 or to the can end flange 6 in any suitable manner.

10 A is the sealing strip, of various preliminary forms as indicated. It may be of angle form in cross section (Figs. 7 and 8) having a horizontal flange 8 and a vertical flange 9, or it may be of U-shape in cross 15 section having parallel flanges 10 (Fig. 9). It may also be straight or of annular form, both of such shapes being illustrated.

The said sealing strip has its top member 10 a little elongated to extend inward 20 slightly over and within the corner of the cover, as shown at 11, to aid in holding the cover from displacement during the processing and subsequent handling. This elongation or lip, being at the extreme edge of the 25 strip member, easily draws upward and outward over the corner of the cover shoulder when the strip is intentionally removed.

When the sealing strip is applied in ring form it may be of U-shape in cross section 30 and sprung or otherwise placed over the can flanges, after which it is compressed by rolls or dies to make permanent hermetic contact of the flanges 2 and 6 with the packing 7. Or it may be of angle shape (Figs. 7 and 8) 35 and applied so that the horizontal flange 8 fits on the cover flange 6, after which the flange 9 is rolled or pressed tightly against the underside of the body flange 2.

When the strip is straight and of U-form 40 or angle shape or other suitable formation, it may be wound onto the can flanges, the latter serving as a former on which the strip is bent into annular contour and rolled or pressed into sealing position.

45 During the operation of applying the sealing strip to the can flanges, or as a subsequent operation, as may be preferred, the strip and interposed flanges 2 and 6 are bent into arch form (Fig. 6) so that said parts 50 are smoothly curved from the inner to the outer boundaries or limits of the flanges and strip. The arch is indicated as upward but it may be downward. The arched form described does not impair or displace the packing 55 7 or detract from the hermetic seal which it aids in effecting; it causes the strip to be held on the can because the strip must move outward, and also turn on itself, on certain precise curved lines as indicated in 60 dotted lines at α (Fig. 6) in order to become detached; and when the can is to be intentionally opened the strip comes smoothly away when pulled downward in the right

direction, not being held to the flanges by any shoulders, offsets or interlocking formations. In order to start the removal of the strip the upper inner corner of its free end is pried up and outward, and as soon as a small portion of the strip has been set free it may be grasped by the fingers, or hand, 70 and pulled off, the can being at the same time turned around.

The seal is illustrated in connection with a round can, but it may be applied to sardine cans of the usual form, or to other cans. 75

The seal herein described is effective and successful for packing goods great quantities of which do not develop high pressure in processing, and probably it can be successfully used in cases where higher pressures are encountered. The force and permanency or durability of the clamping action of the sealing strip depends largely upon the thickness or strength of the metal of said strip, and also upon the sealing pressure which is exerted upon the strip in performing the packing operation. These matters are within the judgment of the skilled operator to attain the best results. 80 85

It will be understood that the flanges 2 and 6 may be given more or less of the arched form in the making of the body and cover, as seen in Figs. 4 and 5. 90

What is claimed is—

1. A removable seal for sheet metal receptacles, the same consisting of a body outwardly flanged around its mouth, a cover formed with a marginal flange and a central depression and shoulder seated in the mouth of the receptacle, and a malleable metal sealing strip embracing the upper and lower faces of the flanges of the body and cover and holding them together to form an hermetic joint, the upper and lower members of said strip and the cover flange and the body flange being arched upward and substantially parallel, the upper member of said strip having a lip extending over and slightly within the corner of the shoulder of said cover. 95 100 105 110

2. A removable seal for sheet metal receptacles, the same consisting of a body outwardly flanged around its mouth, a cover formed with a marginal flange and a central depression and shoulder seated in the mouth of the receptacle, and a malleable metal sealing strip embracing the upper end and lower faces of the flanges of the body and cover and holding them together to form an hermetic joint, the upper member 115 of said strip having a lip extending over and slightly within the corner of the shoulder of said cover. 115 120

In testimony whereof I affix my signature hereto.

WILLIAM E. TAYLOR.
